UNITED STATES PATENT OFFICE.

ROBERT B. BANISTER, OF PROVIDENCE, RHODE ISLAND.

BUTTON-FASTENER.

SPECIFICATION forming part of Letters Patent No. 236,973, dated January 25, 1881.

Application filed August 14, 1880. (Model.)

To all whom it may concern:

Be it known that I, ROBERT B. BANISTER, of Providence, in the county of Providence and State of Rhode Island, have invented a new and useful Improvement in Button-Fasteners, which improvement is fully set forth in the following specification, reference being had to the accompanying drawings, in which—

Figure 1 is a perspective view of my invention; Fig. 2, a partial sectional view. Fig. 3 represents a flat spring-blank before being formed to the shape required; Fig. 4, an enlarged sectional view of the spring after being formed. Fig. 5 is a partial transverse section of a button, *a*, provided with an eye, *d*, in the center.

Any common button with an eye of suitable size may be used in connection with my device.

Near each end of the spring *c* there are formed slight projections *h h*. The spring is bent into a shape something like the letter **U**, as seen in Fig. 4, bringing the ends near together, with the projections *h h* inside and nearly touching each other. The middle or bottom of the spring

is rigidly secured to the center of a back disk, *b* (shown at *b*), leaving the ends of the spring *i i* free.

To attach my device to the button the eye *d* is placed between the ends of the spring and against the projections *h h*. Then, by pressing the back disk and button together, the ends of the spring are forced over the eye of the button, which receives the projections *h* on each side, and the attachment is completed by the reaction of the spring. The parts are easily detached by forcing them apart.

I claim—

In an improved button-fastener, the spring *c*, shaped substantially as shown, rigidly secured to the back disk, *b*, provided at its outer free ends with inner projections, *h h*, and adapted to be forced over the eye of a button, *a*, all substantially as set forth.

R. B. BANISTER.
